UNITED STATES PATENT OFFICE.

EDWARD ERICKSON, OF LYNN, MASSACHUSETTS, ASSIGNOR TO VICTOR SHOE MACHINERY CO., OF BOSTON, MASSACHUSETTS, A CORPORATION OF MASSACHUSETTS.

SHUTTLE FOR SEWING-MACHINES.

1,149,349.

Specification of Letters Patent.

Patented Aug. 10, 1915.

Original application filed December 28, 1912, Serial No. 739,056. Divided and this application filed July 17, 1914. Serial No. 852,098.

To all whom it may concern:

Be it known that I, EDWARD ERICKSON, a subject of the King of Sweden, and a resident of Lynn, in the county of Essex and 5 State of Massachusetts, have invented certain new and useful Improvements in Shuttles for Sewing-Machines, of which the following is a specification.

This invention relates to machines for 10 sewing heavy material such as leather, and refers particularly to that type of such machines known as welt sewing machines.

The object of the invention is to provide 15 an improved shuttle and carrier therefor in a machine such as is shown in another application of mine filed December 28, 1912, Ser. No. 739,056, of which this application is a division, said original application having matured into Patent No. 1,137,198, dated 20 April 27, 1915.

The invention consists in certain novel 25 features of construction and arrangement of parts which will be fully understood by reference to the description of the drawings and to the claims hereinafter given.

Of the drawings: Figure 1 represents a 30 plan view of a machine embodying the principles of the present invention. Fig. 2 represents a detail elevation of the shuttle and its support. Fig. 3 represents a section on line 3—3 of Fig. 2. Fig. 4 represents a view 35 similar to Fig. 3, but showing the bobbin support turned outwardly. Fig. 5 represents a section on line 5—5 of Fig. 2 on an enlarged scale, and Fig. 6 represents a section on line 6—6 of Fig. 5, and also on line 9—9 of Fig. 2, but on a larger scale than Fig. 2.

Similar characters designate like parts 40 throughout the several figures of the drawings.

The base of the machine is provided with two uprights or standards 31, 32. The main shaft 34 is supported in a bearing 35 in the 45 standard 31 and in a bearing 36 carried by a bracket, which is bolted to the side of the standard 32. Said main shaft has a driving pulley (not shown) at one end and at its other end is provided with a spiral gear 39 50 meshing with a pinion 40 secured to a shaft 41 mounted in a bracket 42 supported by the top of the standard 31. The gear 39 and pinion 40 are as 3 to 1. The opposite ends of the shaft 41 are provided with 55 cranks 43, 44 substantially at an angle of

90° to each other. A shaft 45 also mounted in the bracket 42 is provided with cranks 46, 47 at substantially an angle of 90° to each other. A pitman 48 connects the cranks 43 and 46, and a pitman 49 connects the cranks 44 and 47. The pitman 49 has an extension or finger 50, the extreme tip of which forms or carries a lateral pin 51 which enters a recess 52 in the shuttle 53. The connections just described, including 60 the parallel links 48, 49, impart a smooth, uniform motion to the shuttle to rotate the latter three times to each rotation of the main shaft.

Referring especially to Figs. 2, 3 and 4, it 70 will be seen that the shuttle 53 is provided with a rib 54 running in a groove formed in the two-part bearing bracket 55, 56, these two parts of the bearing bracket being formed to present a circular support for 75 the shuttle, one side of the support being open of course to permit the loop of needle thread to be engaged by the hook 9 of the shuttle, carried around the shuttle and removed again therefrom by the takeup. As 80 shown in Figs. 1 and 2, a screw 57 connects the two parts 55, 56 of the shuttle supporting bracket together, attaching bolts 58 securing the two parts of the bearing bracket to the inner face of the standard 31. 85

As best shown in Fig. 1, all of the parts so far described are arranged and mounted to present the shuttle in a plane tangential to the plane of operation of the needle and awl.

The bobbin 59 (Figs. 2, 3 and 4) is rotatably supported upon a pin 60 projecting from an arm 61 pivoted at 62 to the shuttle, said arm 61 having a heel or lateral projection 63, by means of which, as presently 95 described, the bobbin and its support may be locked in the position shown in Fig. 3. A spring 64 secured at one end to the shuttle supporting bracket bears at its other end against the bobbin to hold the bobbin 100 on the pin 60 and also to provide tension to prevent too free unwinding motion of the bobbin. The heel 63 is provided with a pin 65 having a flat side and a round side, as shown in Figs. 5 and 6, said pin 65 being 105 adapted to enter the recess 67 of the latch bolt 66, which is mounted in the shuttle body, a projection 68 at one side of the recess 67 forming a keeper to engage the pin 65 when in the position shown in Fig. 6, 110

and consequently lock the bobbin arm 61 in the position shown in Fig. 3. The engagement of the keeper 68 with the pin 65 is preserved by a spring 69 confined between 5 the inner end of the latch bolt 66 and the plug 70 threaded into the inner end of the aperture for bolt 66. Whenever it is desired to remove the bobbin for rewinding or to substitute another bobbin for it, pressure against the end of the latch bolt 66 by 10 any suitable implement disengages the keeper 68 from the pin 65 so that the operator, by pushing with one finger against the side of the bobbin which sustains the pressure of spring 64, may swing the bobbin and its support to the position shown in Fig. 4 so that the bobbin can easily be removed from the pin 60. By then simply swinging the support 61 from the position shown in 15 Fig. 4 back to the position shown in Fig. 3, the round side of the pin 65, when it contacts with the keeper 68, acts as a cam to displace the keeper 68 to permit the pin 65 to pass it, after which the spring 69 causes 20 the latch bolt 66 to return to the position shown in Fig. 6.

As the mechanism for operating the needle and awl form no part of the present invention, these mechanisms are not herein 30 described. These operating mechanisms are fully described in the application 739,056, to which reference may be made for a more complete description.

The machine is also provided with suitable work feeding devices by which the work may be fed by the awl but it is believed that no description thereof is required in view of the fact that this mechanism forms no part of the present invention. 35

The looper, the loop spreader 216, the needle guide, and the other instrumentalities for forming the stitch, are all fully described in said application 739,056, and are 40 not therefore shown and described in this application.

The shuttle herein shown and described is simple in construction and effective in 45 operation. It is believed that its operation and many advantages will be fully understood without further description.

Having thus described my invention, I claim:

1. In a sewing machine, the combination 50 of a rotary shuttle having a bobbin chamber; a pivoted arm mounted on and movable with said shuttle and having a lateral bobbin support normally positioned within 55 said chamber with its axis coincident with the axis of said chamber, said arm having a heel; and means releasably engaging said 60 heel for positively locking the pivoted arm.

2. In a sewing machine, the combination of a rotary shuttle having a bobbin chamber; a pivoted arm having a bobbin support 65 movable to and from said chamber, said arm having a heel; means releasably engaging said heel for positively locking the pivoted arm; a bracket supporting said shuttle; and a spring secured to said bracket and 70 adapted to bear against the center of the side of the bobbin opposite said arm.

3. In a sewing machine, the combination of a rotary shuttle having a bobbin chamber; an arm pivoted to the shuttle and having 75 a bobbin support movable to and from said chamber, said arm having a heel provided with a pin extending laterally therefrom; and a spring bolt adapted to engage the pin of said heel and lock said arm from 80 movement about its pivot.

4. In a sewing machine, the combination of a rotary shuttle having a bobbin chamber; an arm pivoted to the shuttle and having 85 a bobbin support movable to and from said chamber, said arm having a heel provided with a pin extending laterally therefrom; and a spring bolt adapted to engage the pin of said heel and lock said arm from 90 movement about its pivot, one end of the bolt being exposed for manual operation to release the pin and permit said pivoted arm to be moved outwardly about its pivot.

5. In a sewing machine, the combination 95 of a rotary shuttle having a bobbin chamber; a pivoted arm mounted on and revolute with said shuttle and having a lateral bobbin support adapted to be positioned in the center of said chamber and provided with an inwardly projecting heel; a pin on 100 said heel; and a spring pressed bolt having a shouldered notch therein adapted to coat with said pin to lock said arm.

6. In a sewing machine, the combination 105 of a rotary shuttle having a bobbin chamber; a pivoted arm mounted on and revolute with said shuttle and having a lateral bobbin support adapted to be positioned in the center of said chamber and provided with an inwardly projecting heel; a pin on 110 said heel; a nonrevolute member slidably mounted in a transverse opening in said shuttle and having a recess in one face to receive said pin and a projection to normally retain said pin in said recess; and a 115 spring coacting with said slideable member to retain said projection in the path of said pin.

Signed by me at Boston, Mass., this 18th day of June, 1914.

EDWARD ERICKSON.
